UNITED STATES PATENT OFFICE.

WILLIAM M. BUTTRICK, OF NEW YORK, N. Y., AND RENE P. PIPEROUX, OF WESTWOOD, NEW JERSEY, ASSIGNEES TO CELLULOID CORPORATION, A CORPORATION OF NEW JERSEY.

DESIGN FOR A MIRROR OR SIMILAR ARTICLE.

Application filed December 4, 1928. Serial No. 29,113. Term of patent 3½ years.

To all whom it may concern:

Be it known that we, WILLIAM M. BUTTRICK and RENE P. PIPEROUX, citizens of the United States, and residents of New York, in the county of New York and State of New York, and Westwood, in the county of Bergen and State of New Jersey, respectively, have invented a new, original, and ornamental Design for a Mirror or Similar Article (Case #5), of which the following is a specification, reference being had to the accompanying drawing, forming part thereof.

We claim:

The ornamental design for a mirror or similar article, as shown.

WILLIAM M. BUTTRICK.
RENE P. PIPEROUX.
